CHRISTMAS GIFT SACK

Irwin Goldie, Oakland, Calif.

Application March 20, 1959, Serial No. 55,067

Term of patent 14 years

(Cl. D58—2)

FIG. 1

FIG. 2.

Fig. 1 is a face view, and

Fig. 2 is a back-view of a Christmas gift sack, showing my new design.

The article has inappreciable thickness and has contrasted colored areas with the top band contrasting in color with the remainder of the bag, and with the contrasting tasseled draw cord operating through loops exteriorly of the bag and below the top band, the design for the bag disclosed being characterized by the specific Santa Claus figure shown.

I claim:

The ornamental design for a Christmas gift sack, as shown and described.
